(No Model.)

A. W. MANTLE.
THRASHING MACHINE.

No. 278,716.

Patented June 5, 1883.

ATTEST:

E. B. Bolton
Brooklin

UNITED STATES PATENT OFFICE.

ALFRED WILLIAM MANTLE, OF ECKERNFÖRDE, GERMANY.

THRASHING-MACHINE.

SPECIFICATION forming part of Letters Patent No. 278,716, dated June 5, 1883.

Application filed September 6, 1882. (No model.) Patented in Germany November 17, 1881, No. 18,382; in England March 31, 1882, No. 1,563; in Belgium May 22, 1882, No. 57,999; in France May 24, 1882, No. 149,169, and in Austria-Hungary September 29, 1882, No. 23,692.

To all whom it may concern:

Be it known that I, ALFRED WILLIAM MANTLE, a subject of the Queen of Great Britain, residing in Eckernförde, Germany, have invented certain new and useful Improvements in Thrashing-Machines, of which the following is a specification.

This invention is covered by patents of Great Britain, No. 1,563, dated March 31, 1882; of Belgium, No. 57,999, dated May 22, 1882; of France, No. 149,169, dated May 24, 1882; of Germany, No. 18,382, dated November 17, 1881, and of Austria-Hungary, No. 23,692, dated September 29, 1882.

15 The object of this invention is to simplify and cheapen the construction of thrashing-machines, and also to render them readily adaptable to different kinds of grain.

The accompanying drawing is a vertical longitudinal section of my improved machine, designed to illustrate my invention.

20 A designates the thrashing drum or beater; B, the concave or breasting, and C an inclined chute or chute-board hung beneath the breasting. D is the straw-shaker, and I the frame thereof.

E is the caving riddle or riddles, and K the frame or shoe thereof. The riddle E or its shoe K is suspended by four hangers, H H', one at 25 each corner, (but two of which are shown,) so that it is free to reciprocate in a direction longitudinally of the machine. It is so reciprocated by means of a crank, G, and pitman F, as usual. There should be two cranks and 30 pitmen at opposite sides of the machine. The front end or portion of the straw-shaker D or its frame I is mounted on and fixed to the shoe K, straps X X being preferably used for connecting them. By this means both straw- 35 shaker and caving-riddles are reciprocated together and by the same mechanism, instead of being hung and moved independently, as most commonly heretofore constructed. The straw-shaker D is formed with a hinge or joint, L, near 40 its front end, so that the portion to the rear of this joint may be raised or lowered independently of the portion to the front thereof. This joint may be placed somewhat forward or back of the position shown, or even at the extreme

front end of the shaker, if preferred. The 50 shaker may thus be inclined to various angles to suit it to different kinds of grain, and this without varying the inclination of the caving-riddle on which it is mounted. The rear end of the shaker is supported from the caving-riddle by any suitable adjustable connection, but preferably by a screw, M, and nut N, as shown, so that by rotating this screw in the nut the inclination of the shaker may be easily and accurately adjusted. 55

The chute-board C is suspended by four hangers, H' H', two of which engage its right and left rear corners, while in the construction shown the other two engage the front corners of a shoe, a, to which the chute is fixed 60 rigidly. This shoe is in a distinct compartment of the casing of the machine, separated from the main or thrashing compartment by a partition, b, and the chute C passes freely through an opening in this partition. The object of this construction, which forms no part 65 of my present invention, is to utilize one set of hangers and one reciprocating crank and pitman for hanging and reciprocating both the chute C and shoe a. 70

A crank, G', is formed on the crank-shaft, with its throw to the opposite side from that of the crank G, and a pitman, F', connects this crank with the chute C, by which means the chute and shoe a are reciprocated coincidently with and in opposite directions from the caving-riddle E—that is to say, the chute and riddle move alternately toward and from each other, so that, being approximately of equal weight, each sustains the thrust of the 80 reciprocations of the other, so that the frame of the machine is relieved from strain, and is not subject to undue vibration. The chute C is so arranged that it receives the grain and cavings or short straws which fall through the 85 breasting B, and, by being inclined backwardly, conducts them onto the caving-riddle E. The straw discharged by the beater A is thrown onto the straw-shaker D, where it is agitated and travels to the rear end of the machine, whence it is discharged. The grain that is carried onto the shaker with it is disengaged by its agitation, and falls through the 90 95

shaker onto the caving-riddle E or onto a chute, d, which carries it forward, and finally drops it on this riddle. The caving-riddle inclines to the rear, and by its agitation the cavings are delivered at the rear of the machine, while the grain drops through onto a chute, e, which conveys it to a screen or riddle, f, whence it falls on another chute, g, which delivers it onto a series of screens, h h. 5

10 After falling from chute e, and before reaching screens h h, the grain is subjected to a current of air from a fan, i, which blows out the chaff. This portion of the apparatus constitutes a first cleaning or winnowing mechanism, such as is common to thrashers. The chutes e and g and the screens f and h h are all mounted in a downward continuation of the shoe K, and reciprocate with the caving-riddle E. 15

From the screens h h the grain is conducted 20 to an elevator, j, by which it is carried through an inclined trunk, k, (shown in dotted lines,) to the top of the compartment in which is the shoe a. This shoe contains the screens of a 25 second cleaning or winnowing apparatus, receiving air from a fan, m, by which apparatus the grain is finally cleaned and the several grades are assorted and deposited in separate receptacles. For a more complete description and illustration of this second cleaning and as- 30orting apparatus, reference is made to my application No. 71,241, filed simultaneously herewith.

I claim as my invention—

1. The combination, in a thrashing-machine, 35 of caving-riddle E, shoe K thereof, crank G and pitman F, for reciprocating said shoe and riddle, straw-shaker D, mounted on said shoe above said riddle, so as to necessarily reciprocate therewith, a joint, L, at or near the front 40 end of said shaker, whereby the portion of said shaker to the rear of said joint may be in-

clined to different angles, and an adjustable support interposed between the rear end or portion of said shaker and the shoe, whereby the shaker may be set at any desired inclina- 45

2. The combination, in a thrashing-machine, of the thrashing-drum A, breasting B, reciprocating chute C, arranged thereunder, caving-riddle E, arranged with its higher end beneath 50 the delivering end of said chute and its lower end remote therefrom, suitable means for reciprocating said chute and riddle simultaneously in opposite directions, and the straw-shaker D, arranged above said chute and be- 55 yond the thrashing-drum, and mounted above and fixed to the caving-riddle, so as to reciprocate therewith, substantially as set forth.

3. The combination of caving-riddle E, means for reciprocating it, the straw-shaker D, mount- 60 ed upon and above said riddle, and with its rear end fixed thereto, a hinge or joint in said shaker near or at its rear end, and means for raising or lowering its front end relatively to said riddle, whereby the inclination of the 65 straw-shaker may be adjusted without changing the inclination of the riddle, while both reciprocate together, substantially as set forth.

4. In a thrashing-machine, the combination 70 of the caving-riddle E, shoe K, and straw-shaker D, all suspended by hangers H H, joint L in said straw-shaker, and screw M and nut N, for adjusting the inclination thereof relatively to the caving-riddle, substantially as set forth. 75

In witness whereof I have hereunto signed my name in the presence of two subscribing witnesses.

ALFRED WILLIAM MANTLE.
